JOHAN S. FASTING, OF VALBY, NEAR COPENHAGEN, DENMARK, ASSIGNOR TO F. L. SMIDTH & CO., OF NEW YORK, N. Y., A CORPORATION OF NEW JERSEY.

ROTARY KILN FOR BURNING WET CEMENT MATERIALS, ETC.

Application filed January 13, 1928, Serial No. 246,476, and in Denmark January 27, 1927

Cement slurry, in which the cement materials are held for the time being in suspension in water, is commonly delivered to the feeding end of a rotary kiln through a pipe or chute which discharges the slurry within the feeding end of the kiln. This method of feeding slurry has some recognized disadvantages which it has been proposed to overcome by discharging the slurry through an atomizer nozzle so that the slurry may enter the kiln in a finely divided condition and so lose its water and be subjected the more quickly to the action of the combustion gases within the kiln. This method also has been found in practice to have some disadvantages and it has been the purpose of the present invention to further improve the manner of introducing the slurry into the kiln so that the disadvantages of the old methods may be more completely overcome. In accordance with the present invention the kiln has associated with it, either as a part of the kiln itself or as a part external to the kiln or communicating directly therewith, a slurry receiving chamber into which the slurry is delivered through a pipe or chute or in any suitable manner and in the bottom of which the slurry may accumulate to some extent and from which the slurry is discharged into the path of the combustion gases within the kiln in a finely divided condition under centrifugal action, by a rapidly rotating distributor located in the slurry receiving chamber. The invention will be more fully explained hereinafter with reference to the accompanying drawings in which several embodiments of the invention are illustrated and in which:

Figure 1 is a view in longitudinal sectional elevation showing so much of the feeding end of a rotary kiln with its appurtenances as is necessary to enable the invention to be understood, the slurry receiving chamber being shown as a part of the kiln structure.

Figure 2 is a detail view in section on the plane indicated by the broken line II—II of Figure 1.

Figure 3 is a detail view in section on the plane indicated by the broken line III—III of Figure 1.

Figure 4 is a view similar to Figure 3, but showing a slight modification in the form of the discharging means.

Figures 5 and 6 are views, respectively, similar to Figure 1, but showing slightly different embodiments of the invention.

Figure 7 is also a view in longitudinal sectional elevation, generally similar to Figures 1, 5 and 6, but showing the slurry receiving chamber formed independently of the kiln structure.

Figure 8 is a detail view in section on the plane indicated by the broken line VIII—VIII of Figure 7.

Figure 9 is a view, generally similar to Figures 1, 5 and 6, showing still another embodiment of the invention.

Figure 10 is a view in section on the plane indicated by the broken line X—X of Figure 9.

Figure 11 is a partial, detail view on a larger scale illustrating different forms of the distributing device.

In the embodiment of the invention illustrated in Figures 1, 2 and 3 the kiln 1, of which only the upper or feeding end is shown, is projected into the kiln head 2. The slurry in this instance, is delivered through a chute 3 and is discharged, as indicated at 4, into a slurry receiving chamber 4^a which is shown as a part of the kiln structure itself, being defined by an annular partition 5. A shaft 6, suitably supported in bearings outside of the kiln head and rotated at relatively high speed by any convenient means, sufficiently represented by the pulley 7, is extended into the slurry chamber 4^a and bears discs 8, two of which are shown as plain discs, while the other two are shown as supporting between them wings 9, adapted to swing on pins 10 supported by the discs. This distributing device, as indicated in Figure 1, dips into the slurry which may be permitted to accumulate somewhat in the bottom of the rotating slurry chamber and takes up the slurry which, under the influence of centrifugal action, is thrown off in a finely divided condition into the path of the combustion gases, as indicated in Figures 2 and 3. The contact surface between the slurry and the com-

bustion gases is thus made very large and the slurry is brought into contact with practically all of the combustion gases and is thereby caused to lose its water and to be subjected very quickly to the action of the combustion gases.

In the embodiment of the invention shown in Figures 1, 2 and 3, the discs 8 are assumed to be fixed on the shaft 6 so as to rotate therewith, but, as shown in Figure 4 the distributing discs 8^a might be annular and disposed loosely on a sleeve 11 secured to the shaft 6.

In the embodiment of the invention shown in Figure 5 the slurry chamber 1^a is also formed as a portion of the kiln structure, but is shown as of larger diameter and as provided with radial vanes 12 and inclined vanes or scoops 13 by which such portion of the partly dried slurry as may accumulate at the bottom of the slurry chamber, near its discharge end, is taken up in the rotation of the slurry chamber with the kiln and is discharged into the drying or burning zone of the kiln. In other respects the construction is the same as already described with reference to Figure 1 except that the shaft 6 is shown as parallel with the axis of the kiln.

In the embodiment of the invention shown in Figure 6 the slurry chamber 1^b is also formed as part of the kiln structure, but is frusto-conical in shape while the shaft 6 is not only pitched at such an angle as to throw the slurry toward or partly within the kiln, but is hollow and provided near the discs 8 with discharge openings 14 through which the semi-liquid slurry, received from the chute 3, is discharged into the slurry chamber.

In the embodiment of the invention shown in Figures 7 and 8 the slurry chamber 1^c is not only segmental in cross-section but does not rotate with the kiln structure 1, being mounted independently thereof on a fixed support. The kiln structure is formed at its end with an annular flange 16 and the slurry chamber 1^c is formed with a flange 15 which is projected slightly into the kiln 1. In this instance the slurry is discharged through a funnel 17 upon the inclined rear wall 17^a of the slurry chamber, which is provided with a flue 18 to conduct combustion gases to the usual stack. The shaft 6 in this instance is provided with discs 8 as before, and is also provided with a helix 19 which serves not only to distribute the slurry as before but to feed the partially dried slurry forward into the kiln.

In the embodiment of the invention shown in Figure 9 the slurry chamber 1^d is arranged to rotate with the kiln structure 1 but is separated from the extended wall 20 of the kiln structure by an annular space 21. The kiln head 2^a is formed with a flange 22 to project slightly within the kiln through the annular end wall 23 and is also formed with an in-

clined bottom 24 from which such dried slurry as may settle thereon out of the combustion gases on the way to the stack is returned to the kiln to be fed through the annular space 21 and so returned to the drying or burning zone of the kiln without passing through the slurry chamber 1^d. The slurry is delivered through the chute 3 directly within the slurry chamber as indicated at 4. As indicated in Figure 10, two shafts 6 with their discs 8 might be arranged side by side and each shaft 6 might be provided at its extremity with a conveyor wheel 27 to promote the passage of the partly dried slurry into the drying or burning zone of the kiln.

It will be understood that the distributing device might be made up of a series of flat discs, as shown in the several figures of the drawings already referred to, or that one or another or all of the discs might be variously shaped as shown in Figure 11 in which the disc 8^b has its edge bent slightly toward the burning zone of the kiln, the disc 8^c has its peripheral portion waisted or corrugated, the disc 8^d is formed in its peripheral portion with holes 25 and the disc 8^e is provided on the side next the burning zone with vanes 26.

It will also be understood that various other changes might be made to suit different conditions of use, different degrees of consistency of the slurry, etc., and that, except as pointed out in the accompanying claims, the invention is not restricted to any particular construction shown and described herein.

I claim as my invention:

1. The combination of a rotary kiln, a slurry chamber in communication therewith, means to deliver the slurry to said chamber, a rotary distributing device in the slurry chamber to dip into the slurry therein, and means to rotate the said device at relatively high speed to discharge the slurry into the chamber in a finely divided condition under the influence of centrifugal action.

2. The combination of a rotary kiln, a slurry chamber in communication therewith, means to deliver the slurry to said chamber, a shaft provided with discs to dip into the slurry in said chamber, and means to rotate said shaft at relatively high speed to discharge the slurry from said discs in a finely divided condition into the burning zone of the chamber under the influence of centrifugal action.

3. The combination of a rotary kiln, a slurry chamber formed to rotate therewith, means to deliver the slurry to said chamber, a rotary distributing device in the slurry chamber to dip into the slurry therein, and means to rotate the said device at relatively high speed to discharge the slurry into the kiln in a finely divided condition under the influence of centrifugal action.

4. The combination of a rotary kiln, a slurry chamber arranged to rotate with the

kiln in the extended wall thereof and separated from the extended wall of the kiln by an annular space, means to deliver slurry within the slurry chamber, a rotary distributing device arranged in the slurry chamber at the bottom thereof, means to rotate said device at a relatively high speed, and a kiln head

having a sloping bottom to deliver to the space between the slurry chamber and the ex-wall of the kiln the dried slurry which settles on the 10 sloping bottom from the combustion gases.

This application signed this 30th day of December A. D. 1927.

JOHAN S. FASTING.
